UNITED STATES PATENT OFFICE.

RUDOLF M. OSTERMANN, OF EVANSTON, ILLINOIS, ASSIGNOR TO THE SUPERHEATER COMPANY, OF NEW YORK, N. Y., A CORPORATION OF DELAWARE.

INJECTOR.

Application filed February 18, 1924. Serial No. 693,451.

To all whom it may concern:

Be it known that I, RUDOLF M. OSTERMANN, a citizen of the United States, and a resident of Evanston, Cook County, State 5 of Illinois, have invented certain new and useful Improvements in Injectors, of which the following is a specification.

This invention relates to injectors and more particularly to that type of injector 10 disclosed in the United States Letters Patent No. 1,342,128 granted June 1, 1920, to James Metcalfe et al. wherein is shown an injector adapted to be operated by low pressure exhaust steam.

With injectors of this type, it is necessary 15 to reduce the amount of water admitted to the injector whenever the pressure of the exhaust steam falls below a value sufficient to insure the continuity of the water jet delivered thereby; this reduction of the water is usually accomplished by means of a manually operated handle which controls a movable cone within the injector. In addition to the manual regulation of the water these 20 injectors are also provided with a supplementary live steam nozzle to assist the steam action of the low pressure steam nozzle, and while the admission of a supplementary supply of live steam is effective to assist the 25 exhaust steam action, it necessarily involves the manipulation of additional controlling means, and is subject to the further objection that it increases both the maximum and minimum water delivery of the injector and 30 therefore does not have any marked influence upon the working range of the injector.

It is an object of the present invention to provide in an injector of this type a new and improved construction by means of 35 which the flow of the low pressure exhaust steam through the injector is automatically controlled either by an element directly actuated by the variations in the pressure of the exhaust steam, or by some element that 40 would be substantially indicative of the changes in the pressure thereof.

A further object is to provide an exhaust steam injector which will permit the range 45 of water delivery to be substantially increased.

Another object is to provide adjusting means, interconnected in such a manner with the means for automatically controlling the flow of the exhaust steam, that the amount 50 of water delivered to the injector may be

varied without interfering with the automatic operation thereof.

These and further objects will be apparent to one skilled in the art to which the invention appertains by reference to the 60 following detailed description and the accompanying drawings forming a part hereof, wherein are illustrated typical examples of installations constructed in accordance with the principles of my invention. 65

Fig. 1 is a central longitudinal horizontal section on the line 1—1 of Fig. 2 through an injector embodying my invention.

Fig. 2 is a side elevation of a portion of the injector shown in Fig. 1. 70

Fig. 3 is a section on the line 3—3 of Fig. 1.

Fig. 4 is a diagrammatic illustration of a modified form of an installation.

Figs. 5 and 6 are sectional details of 75 parts of the installation shown in Fig. 4.

Fig. 7 is an illustration of another modified form of an installation.

Referring to Figs. 1 to 3 of the drawings the numeral 10 indicates the main casing of 80 the injector which contains therein a main exhaust steam nozzle 11, a water cone or preliminary mixing nozzle 12, a combining nozzle 13, a delivery nozzle 14, and a further preliminary mixing nozzle 15 between 85 the water cone and combining nozzle, all as more particularly set forth in the aforementioned patent to Metcalfe, et al.

The main exhaust steam nozzle 11 is movable longitudinally of casing 10 to vary the 90 annular water inlet formed between the outer surface of the nozzle 11 and the inner end of the water cone 12, and to control the amount of water drawn through the intake opening 11^a, as in the structure disclosed 95 in said patent, but instead of the manually operated handle employed in such structure to move said nozzle 11, I provide an internally screw-threaded bushing 16, rotatably mounted within the casing 10 and having a 100 plurality of gear teeth 17 upon its outer circumference. The main exhaust steam nozzle is screw-threaded, as at 18, to engage within the bushing 16. Suitable packing as indicated at 19 is inserted between the bushing 16 and casing 10, and the bushing is restricted from movement longitudinally of the casing by any suitable means. 105

A rack 20 for rotating bushings 16 is slidably mounted in a boss 21 of casing 10 and 110

meshes with the gear teeth 17 of bushing 16, said rack being shown as a grooved rod which projects through a stuffing box 22 on said boss, and is pivotally connected, as at 5 23, to one end of a lever 24. In order to prevent rotation of the main exhaust nozzle 11, the nozzle is provided with a laterally projecting boss 25 which is suitably apertured to receive a pin or stud 26 fixed within the 10 end wall of the water cone 12.

Rotatably mounted within a flanged collar-like extension 27, secured, as by bolts 28, to the flanged end 29 of casing 10 is an internally screw-threaded bushing 30, having 15 gear teeth 31 on its outer circumference with which a rack 32 engages. Rack 32 is slidably mounted within a boss 33 on the extension 27 and its projecting outer end is pivotally connected at 32^a, to the other end 29 of lever 24, the construction of bushing 30, rack 32 and boss 33 being similar to the bushing 16, rack 20 and boss 21, except that the screw-threads of the bushings 30 and 16 are opposite in direction.

25 A member in the form of a spider 34 terminates at its inner end in a cone-shaped surface 35, to provide a valve member which is spaced from the larger end of the inner wall of the main exhaust nozzle 11 to form 30 an annular space through which the exhaust steam passes to the said nozzle, while the other end of the spider is formed into an annular, externally screw-threaded collar 34^a to engage with the threads of bushing 30 for 35 the purpose of moving the spider 34 longitudinally of the injector to vary the size of said annular space.

The spider 34 forms a part of the live steam nozzle and is provided with a boss 36 40 having a central bore 37, through which the live steam passes, and a counter bore 38 which is slidably mounted over the live steam admission pipe 39, pipe 39 extending through the manifold 40 and being connected with the live steam conduit 41. A key or pin 43 is fixed to pipe 39 and engages 45 in a suitable key-way or slot 44, within the boss 36 of spider 34, to prevent rotation thereof while permitting longitudinal movement 50 of the spider.

The inner flange of the flanged collar-like extension 27 is provided with an apertured boss 46 to which the by-pass 47 is connected, said by-pass leading a portion of the steam 55 to the space between the water cone 12 and the further preliminary mixing nozzle 15 to provide an outer envelope of steam about the combined jet issuing from the nozzle 15 between the water cone and combining nozzle. 60 The opening to the boss 46 from the injector is located between the bushings 18 and 30 and a small valve 48 which is suitably secured to the spider 34 is adapted, when the spider 34 is moved towards the main exhaust steam nozzle, to move across and close the 65

opening of the boss 46 to an extent substantially proportional to the throttling of the annular space between the nozzle 11 and water cone 12.

Mechanism is provided for causing the lever 24 to be actuated in accordance with variations of the pressure in the exhaust steam line and a suitable embodiment of such mechanism is illustrated in Fig. 2 of the drawings. Intermediate the ends of lever 75 24 and preferably centrally thereof, is pivotally secured one end of a longitudinally adjustable rod 50, the other end of which is secured to one end of a lever 51. To the other end of lever 51 is pivotally connected a piston rod 52 which is secured to a suitable piston 53, slidably mounted in a cylinder 54, which cylinder is connected, as by the pipe 55, with any suitable point of the exhaust steam line. A coiled spring 56, mounted 80 within the cylinder between the upper end thereof and the piston 53 is provided for urging the piston against the pressure of the exhaust steam.

Means are provided for varying the positions of the spider 34 and cone 11 to regulate the range of water delivery of the injector, and such means may comprise a manually adjustable rod 57 having its inner end connected with the pivotal connection 23 of the lever 24, while its outer end is extended to any conveniently accessible point and is screw-threaded to receive the hand wheel 58.

The manner in which the form shown in Figs. 1 to 3 operates is as follows: it being 100 assumed that the hand wheel 58 is set to adjust the positions of the steam nozzle 11 and spider 34 to secure the desired amount of water delivery, increase in the pressure of the exhaust steam will move piston 53 105 against the action of spring 56, thereby causing lever 51 to rock upon its pivot and move the rod 50 downwardly, thus causing lever 24 to be moved about the pivotal connection 23 and actuate the spider 34 towards the main exhaust nozzle 11 to decrease the annular space through which the exhaust steam flows, the valve 48 also being carried across the opening of the boss 46 to an extent substantially proportional to the throttling of the annular space between the exhaust steam nozzle 11 and the water cone 12.

Similarly, when the pressure of the exhaust steam decreases, the piston 53 will be moved in the opposite direction by the action of the spring 56, and thereby will actuate the parts in a reverse manner to increase said annular space. It will be seen that in this way the annular space through which the exhaust steam flows will be varied and that the velocity of the steam flow will be controlled in accordance with the variations in the pressure of the exhaust steam. As the injector effect is most stable with a given 115 weight of steam passing through the in- 120 125

jector, it will be understood that in order to maintain the injector effect substantially constant, the annular opening between the spider 34 and nozzle 11 should be decreased 5 when the pressure of the exhaust steam increases and decreased as the pressure falls.

During the automatic operation of the device by the cylinder and piston, the pivotal connection 23 will act as a fulcrum for the 10 lever 24 thus causing rack 32 to be moved, the rack 20 meanwhile being held stationary by the rod 57; on the other hand when the hand wheel 58 is operated the lever 24 will pivot upon its pivotal connection with the 15 rod 50; with this arrangement the racks 20 and 32 will be shifted in opposite directions so that longitudinal movement of the rod 57 in one direction will simultaneously cause the annular inlets for the water and steam 20 to be restricted, and in the reverse direction will cause the annular inlets to be increased. It will be noted that the threads of the bushings 16 and 30 are arranged to produce this movement of the nozzle 11 and spider 34 25 respectively, and that the pitch of the threads of the bushing 30 is greater than the threads of bushing 16, so that, when the nozzle 11 is moved a certain distance by the hand wheel 58 and rod 57, the spider 34 30 will be moved a proportionately larger distance but in the same direction, this being necessary because a variation of the quantity of water requires a greater variation in the quantity of steam supplied.

35 Figs. 4 to 6 illustrate an installation in which the movement of the spider 34 is effected by an apparatus connected with an element of a locomotive engine, the movement of which element is indicative of variations in the pressure of the steam exhaust line. The numeral 60 indicates the valve rod of a locomotive to which is secured a collar 61. A lever 62 pivotally mounted intermediate its ends, has one end thereof pivotally connected to the collar 61, while its other end is pivotally secured to a piston rod 63 of a piston 64 slidably mounted within a cylinder 65 formed on the lower part of a fluid container 66.

50 Communication between the fluid container 66 and the cylinder is furnished through a suction valve 67. A conduit 68 leads from the end of cylinder 65 to a valve casing 69, in which a pressure valve 70 is located at the delivery end of the conduit 68. One end of a pipe line 71 is secured to the valve casing 68, and its other end leads to the lower part of a fluid pressure cylinder 72 mounted adjacent to the injector 10, the 55 construction of the injector being identical with that shown in Fig. 1. An aperture 73 which is controlled by a needle valve 74 permits a portion of the fluid delivered by the pump 65 to be by-passed into the fluid contained 60 66. The fluid pressure cylinder 72

has slidably mounted therein a plunger 75 which is connected by the plunger rod 76 with the lever 24, which lever is connected to the racks 20 and 32 of the injector; an adjusting rod 57 and handle 58 being provided all as shown in Figs. 1 to 3 inclusive. A coiled spring 77 is confined between the head of cylinder 72 and the plunger 75 and serves to urge the plunger against the pressure of the fluid from the pipe line 71.

75 The operation of the installation shown in Figs. 4 to 6 inclusive is as follows: The reciprocation of valve rod 60 causes the piston 64 to be reciprocated, thus withdrawing the fluid from the fluid container 66 and forcing it through conduit 68 into the pipe line 71. Needle valve 74 may be adjusted to cause a portion of the fluid delivered by the pump to be by-passed through the aperture 73 from the valve casing 69 into the fluid container 66, it being understood that the size of the aperture 73 is only sufficient to permit a small portion of the fluid to pass into the fluid container and that when the needle valve 74 is opened, it will only be opened to an extent required to regulate the pressure of the fluid within the pipe line 71 and cylinder 72. For any given setting of the needle valve 74, the pressure within the pipe line 71 will obviously be closely dependent upon two factors, viz—the main valve travel, as governing cylinder cut-off, and the speed of the engine, and as these two factors are fairly indicative of the exhaust steam pressure, the pressure of the fluid, within the pipe line 71 and cylinder 72, therefore changes in accordance with variations of the pressure of the exhaust steam.

90 As the cut-off of the main valve of the engine is regulated by the reverse lever of the locomotive, Fig. 7 shows another form of an installation in which the position of the lever 24 is controlled by the position of the reverse lever 80. For this purpose the center of lever 24 is connected by a link 81, to one arm 82 of a bell crank, the other arm 83 of which lies within the path of a lug 84 which projects outwardly from the side of the reverse lever 80. A spring 86 normally holds the arm 82 of the bell crank lever in engagement with a stop 87, as shown in Fig. 7. When the lever 80 is thrown to the normal forward working position, the lug 84 will engage the arm 83 of the bell crank and move the lever 24 to positions corresponding to the positions of the reverse lever, thereby making the positions of the racks 20 and consequently the spider 34 dependent upon the positions of the reverse lever. I have hereinabove shown various means for operating, in accordance with exhaust steam conditions, the spider 34 which, in cooperation with the main steam nozzle 11, controls the passage of exhaust steam through the injector. One of these means includes a cylinder and pis-

ton (Fig. 2), the latter being under the direct influence of the exhaust steam. Others of these means are parts of the engine, the movement of which is in proportion to the exhaust steam pressure (Figs. 4 and 7), the latter being determined by such movement. When I refer, in one of my claims, to an element of the engine which is indicative of the exhaust steam condition, I intend to indicate thereby all such means.

It will be understood, that the disclosure contained herein is to be considered as illustrative and not in a limited sense and that changes, variations and modifications may be resorted to without departing from the spirit of my invention.

Having thus disclosed my invention, I declare that what I claim as new and desire to secure by Letter Patent of the United States is,

1. In a steam injector adapted to be operated by the exhaust steam from an engine, a main exhaust steam nozzle, means to regulate the position of said nozzle to vary the quantity of water passing through said injector, a member adjacent to said main nozzle and co-operating therewith to form a passage for the exhaust steam flowing through said injector and mechanism connected with said member to control automatically the extent of opening of said passage in accordance with variations in the steam exhaust conditions of the engine.

2. In a steam injector adapted to be operated by the exhaust steam from an engine, a main exhaust steam nozzle, means to regulate the position of said nozzle to vary the quantity of water passing through said injector, a member adjacent to said main nozzle and co-operating therewith to form a passage for the exhaust steam flowing through said injector and mechanism connected with said member and the exhaust steam line and operated directly by variations in the pressure of the exhaust steam to control automatically the extent of the opening for the passage of the exhaust steam.

3. In a steam injector adapted to be operated by the exhaust steam from an engine, a main exhaust steam nozzle, means to regulate the position of said nozzle to vary the quantity of water passing through said injector, a member adjacent to said main nozzle and co-operating therewith to form a passage for the exhaust steam flowing through said injector and connections between said member and nozzle to move them simultaneously in the same directions.

4. In a steam injector adapted to be operated by the exhaust steam from an engine, and provided with means to regulate the amount of water delivered to the injector; a valve member to regulate the extent of opening for the passage of the exhaust steam through said injector, and mechanism con-

nected with said valve member to control automatically the flow of exhaust steam through said injector in accordance with variations in the exhaust steam conditions of the engine.

5. In an injector adapted to be operated by the exhaust steam from an engine, a main exhaust steam nozzle, means to move said nozzle to vary the amount of water flowing through the injector, a bushing rotatably mounted within said injector, an exhaust steam regulating member having screw threaded engagement with said bushing and mechanism to rotate said bushing and move said member longitudinally of said nozzle.

6. In an injector adapted to be operated by the exhaust steam from an engine, a main exhaust steam nozzle, means to move said nozzle to vary the amount of water flowing through the injector, a bushing rotatably mounted within said injector, an exhaust steam regulating member having screw threaded engagement with said bushing, mechanism to rotate said bushing and move said member longitudinally of said nozzle, and devices connecting said mechanism with an element of the engine which is indicative of the exhaust steam condition to cause said member to be actuated automatically and responsively to variations of the steam exhaust conditions of the engine.

7. In an injector adapted to be operated by the exhaust steam from an engine, a main exhaust steam nozzle, means to move said nozzle to vary the amount of water flowing through the injector, a bushing rotatably mounted within said injector, an exhaust steam regulating member having screw threaded engagement with said bushing mechanism to rotate said bushing and move said member longitudinally of said nozzle, and means to prevent rotation of said member while permitting longitudinal movement thereof.

8. In an injector adapted to be operated by the exhaust steam from an engine, a pair of screw threaded bushings rotatably mounted within said injector, a main exhaust steam nozzle having screw threaded engagement with one of said bushings, an exhaust steam regulating member having screw threaded engagement with the other of said bushings, means to prevent rotation of said nozzle and member while permitting longitudinal movement thereof and mechanism to rotate said bushings.

9. In an injector adapted to be operated by the exhaust steam from an engine, a pair of screw threaded bushings rotatably mounted within said injector, a main exhaust steam nozzle having screw threaded engagement with one of said bushings, an exhaust steam regulating member having screw threaded engagement with the other of said bushings

means to prevent rotation of said nozzle and member while permitting longitudinal movement thereof, the screw threads of said bushings being opposite in direction, and adjusting mechanism to simultaneously rotate said bushings in opposite directions to produce simultaneous movements of said steam nozzle and member in the same direction longitudinally of said injector.

10. In a injector adapted to be operated by the exhaust steam from an engine, a pair of screw threaded bushings rotatably mounted within said injector, a main exhaust steam nozzle having screw threaded engagement with one of said bushings, an exhaust steam regulating member having screw threaded engagement with the other of said bushings, means to prevent rotation of said nozzle and member while permitting longitudinal movement thereof, devices for rotating each of said bushings and connections between said devices.

11. In an injector adapted to be operated by the exhaust steam from an engine, a pair of screw threaded bushings rotatably mounted within said injector, a main exhaust steam nozzle having screw threaded engagement with one of said bushings, an exhaust steam regulating member having screw threaded engagement with the other of said bushings, means to prevent rotation of said nozzle and member while permitting longitudinal movement thereof, devices for rotating each of said bushings, connections between said devices, and an adjustable rod connected with said connections to produce a simultaneous adjustment of said nozzle and member.

12. In an injector adapted to be operated by the exhaust steam from an engine, a controlling device to regulate the amount of water delivered to said injector, a member to control the extent of the opening through which the exhaust steam flows in its passage through the injector, mechanism for operating said controlling device and member including connection between said device and member and a manually adjustably rod connected with said mechanism to produce simultaneously proportional adjustments of the said controlling device and member.

13. In an injector adapted to be operated by the exhaust steam from an engine, a controlling device to regulate the amount of water delivered to the injector, a member adjacent to said controlling device and defining therewith a passage through which the exhaust steam passes in flowing through the injector, mechanism connected with said member to operate it automatically in re-

sponse to variations in the steam exhaust 60 conditions of the engine and an adjusting rod connected with said mechanism to adjust simultaneously said controlling device and member for varying the water delivery without varying the extent of movement of said 65 member produced by changes in the exhaust steam condition of the engine.

14. In an injector adapted to be operated by the exhaust steam from an engine, a controlling device to regulate the amount of 70 water delivered to the injector, a member for controlling the flow of exhaust steam through said injector and mechanism connected with the exhaust steam line of the engine and said member for automatically 75 controlling the position of said member responsively to the variations in the pressure within said exhaust steam line.

15. In a steam injector adapted to be operated by the exhaust steam from an engine, 80 and having a main steam nozzle and a water cone adjacent thereto, a conduit to by-pass a portion of the steam around said main steam nozzle and water cone, a member adjacent to said main steam nozzle and cooperating therewith to form a restricted passage for the steam flowing to said main nozzle, mechanism connected with said member to control automatically the extent of opening of said restricted passage in accordance with 90 variations in the steam exhaust conditions of the engine, and a valve connected with said member and extending towards the opening of said conduit to control the quantity of steam by-passed about said main 95 steam nozzle and water cone in accordance with the extent of opening of said restricted passage.

16. In an injector adapted to be operated by the exhaust steam from an engine, a pair 100 of screw threaded bushings rotatably mounted within said injector, a main exhaust steam nozzle having screw threaded engagement with one of said bushings, a member having screw threaded engagement with the 105 other of said bushings, means to prevent rotation of said nozzle and member while permitting longitudinal movement thereof, the screw threads of said bushings being opposite in direction, and of different pitch, 110 an adjustable rod to rotate simultaneously said bushings in opposite directions to produce simultaneous movements of said member and steam nozzle in the same direction but of different extent longitudinally of said 115 injector.

RUDOLF M. OSTERMANN.
